[57] CLAIM

The ornamental design for a chaise frame, as shown and
described.

DESCRIPTION

FIG. 1 is a perspective view of a chaise frame showing
my new design;

FIG. 2 is a side elevational view, the opposite side being
a mirror image thereof;

FIG. 3 is a top plan view;

FIG. 4 is a bottom plan view;

FIG. 5 is a front elevational view; and

FIG. 6 is a rear elevational view thereof.
